UNITED STATES PATENT OFFICE.

LOUIS W. AUSTIN, OF WASHINGTON, DISTRICT OF COLUMBIA, ASSIGNOR TO NATIONAL ELECTRIC SIGNALING COMPANY, OF PITTSBURG, PENNSYLVANIA, A CORPORATION OF NEW JERSEY.

RECEIVER.

No 846,081.

Specification of Letters Patent.

Patented March 5, 1907.

Application filed October 27, 1906. Serial No. 340,845.

To all whom it may concern:

Be it known that I, LOUIS W. AUSTIN, a citizen of the United States, and a resident of Washington, in the District of Columbia, have invented certain new and useful Improvements in Receivers, of which the following is a specification.

The invention herein described relates to certain improvements in receivers for electric receiving, and more especially for signaling by electromagnetic waves.

The invention is hereinafter more fully described and claimed.

In the accompanying drawing, forming a part of this specification, the figure is a dia-grammatic view illustrating my improvement.

In a previous application I have described and claimed a receiver for electromagnetic waves consisting of a thermo-electric couple having one of its members or elements formed of tellurium, the other being formed of aluminium or other suitable metal or alloy.

I have found that a thermo-electric element consisting of tellurium and silicon or alloys of these metals is especially sensitive and possesses many advantages as a receiver for electromagnetic waves.

In the drawing forming a part of this specification, 7 is an aerial grounded, as shown. 30

3 is a wedge-shaped piece of tellurium mounted on a wire 4, and 1 is a rod of silicon mounted on a hard-rubber sheet 2.

6 is an adjusting-spring controlled by the screw 5. 35

8 is a telephone-receiver. On the passage of the electrical oscillations through the thermo-couple formed of the elements 1 and 3 the telephone produces an indication or signal.

What I claim is— 40

1. In a system of signaling, a receiver consisting of a thermo-couple having as its elements tellurium and silicon.

2. In a system of signaling by electromagnetic waves, a receiver consisting of a thermo-couple having as its elements tellurium and silicon. 45

Signed at Brant Rock, Marshfield town-ship, in the county of Plymouth and State of Massachusetts, this 24th day of October, A. D. 50 1906.

LOUIS W. AUSTIN.
